UNITED STATES PATENT OFFICE

135,376

DESIGN FOR AN ASH TRAY

Maurice Britz, Chicago, Ill.

Application January 13, 1943, Serial No. 109,258

Term of patent 3½ years

To all whom it may concern:

Be it known that I, Maurice Britz, a citizen of the United States of America, residing at 314 Institute Place, Chicago, county of Cook, and State of Illinois, have invented a new, original, and ornamental Design for an Ash Tray, of which the following is a specification, reference being had to the accompanying drawing, forming a part thereof.

Fig. 1 is a top plan view of an ash tray embodying my new design; Figs. 2 and 3 are side elevational views showing the details of two of the base segments and Fig. 4 is a side elevational view of the third base segment, the jar portion being omitted for convenience of illustration.

I claim:

The ornamental design for an ash tray, substantially as shown.

MAURICE BRITZ.
